COMBINED CONTAINER AND TOY BUILDING BLOCK

Harvey R. Stolte, Ellicott City, Md.

Application December 28, 1948, Serial No. 67,717

1 Claim. (Cl. 215—10)

1

This invention relates to containers, and more particularly to containers which are particularly suitable for merchandising foodstuffs of the character commonly used in the feeding of small children.

It is an object of this invention to provide a container as just referred to which is of improved construction so that after it has served its purpose as a container for food it may be used as a toy building block.

Another object of this invention is to provide a container as referred to which is of improved construction which facilitates erection when used as a toy building block and which at the same time facilitates stacking for purposes of transportation, storage, display, etc.

Another object of this invention is to provide an improved container as hereinabove referred to which does not interfere with the making of proper airtight seals when the container is to serve its purpose as a container for food.

Other objects will appear as the description of the invention proceeds.

The invention is capable of receiving a variety of mechanical expressions one of which has been illustrated on the accompanying drawing, but it is to be expressly understood that the drawing is for purposes of illustration only, and is not to be construed as a definition of the limits of the invention, reference being had to the appended claim for that purpose.

Referring in detail to the accompanying drawing, wherein the same reference characters are used to designate corresponding parts in the several figures,

Fig. 1 is a perspective view of the improved container with a part of its outer wall broken away;

Fig. 2 illustrates how the containers may be stacked when used either as food containers or as toy building blocks; and

Fig. 3 is a cross section on the line 3—3 of Fig. 2.

The container has a hollow body 10 that is polygonal in horizontal sections. In the form shown, the body 10 comprises four side walls 11, a top 12 and a base 13 which together, except for the collar hereinafter referred to, approximate a cube, having six right angularly disposed faces. While the body in planes parallel to its base is shown as square in cross section as preferred, as is usual with toy building blocks, other polygonal cross sections may be used to provide blocks of more than four side walls.

Internally said container has a chamber 14

2

which in cross section in planes parallel to the base of the container preferably has the same contour as the exterior of the container, i. e., the chamber is square in cross section so that the side walls thereof are of approximately equal thickness throughout.

The top wall 15 lies in a plane at right angles to the side walls 11 except that, centrally arranged thereon, is an upstanding circular collar 16 constructed in any suitable way so as to receive an airtight closure member 17. As illustrated, said collar 16 is shown as provided with an overhanging tapered flange 18 such as conventionally used on glass jars when a metal closure member is to be sealed therearound, but as will be apparent to those skilled in the art if a threaded closure member is preferred the collar 16 may be appropriately threaded to receive the same.

The bottom 13 of the container has its outer surface 19 in a plane at right angles to the side walls 11, and it is made thicker than the top and side walls so as to receive a recess 20 opening from the bottom of the container and leaving an intermediate partition 21 constituting the bottom wall of the chamber 14. Recess 20 is of such cross section that it slidingly receives, as a loose fit, the upstanding neck 16 and closure member 17 on another container of like construction when two containers are stacked together as shown at 22 in Fig. 2. Recess 18 may be circular in cross section as shown in Fig. 3, conforming with the contour of the collar 16, but other contours having straight sides tangent to the periphery of the neck 16 with its closure member 17 may be used

with like effect if it is desired to lighten the construction by having less material in the bottom 13. Thus the recess may be square in cross section, its sides being extensions of the side walls of the chamber 14 as shown at 23 in Fig. 1, the transverse dimensions of the recess approximating the diameter of the collar 16 with its closure member 17.

The side walls of the container may be provided with letters as shown at 24, or pictorial illustrations of articles as shown at 25, or both, as is conventional in the case of toy building blocks where the same blocks on different sides for example may carry a capital A and a picture of an apple, etc.

The container may be made of any suitable material such as would be appropriate for the foodstuff to be packed and for subsequent use as a building block. To avoid breakage and injury to children while playing with the blocks, readily

frangible materials should be avoided. Synthetic resin products are preferable because, when desired, the walls of the blocks may be made transparent to show the content of the chamber 14 when serving its purpose as a food container, while such products facilitate construction because of their ready moldability.

The chamber 14 may be readily filled with any suitable foodstuff, such as commonly used by small children, after which the container may be sealed at the factory by proper application of the closure member 17. When assembled for transportation, storage, etc., the polygonal cross section of the containers facilitates compact assembly, while the recesses 20 in the bottom of each container, guidingly receiving the closed top of another container, as shown at 22 in Fig. 2, facilitate assembly in vertical directions. This construction also enables the containers to be readily stacked on shelves, in show windows, etc., because the interlocking relationship established between the recessed bottoms and collared tops of contiguous containers when stacked provides a particularly stable arrangement.

In the hands of the consumer the closure member 17 may be readily removed, and after the content of the container is used, a light, strong toy building block is left which has the advantage that when the blocks are placed one on another as shown at 26 in Fig. 2 the collars 16 are guidingly received in the recesses 20 with only slight play, providing stability for the erection.

It will therefore be perceived that the present invention provides a polygonal container for foodstuffs which when emptied becomes an advantageous toy building block. The container is of such construction that both when used as a container and as a toy building block stacks formed thereof have particular stability. At the same time the construction is such that there is no interference with the usual airtight sealing of the containers when the same is used for foodstuffs. The container can also be readily made of moldable material that is light and strong and safe for children to play with.

While the embodiment of the invention illustrated on the drawing has been described with considerable particularity, it is to be expressly understood that the invention is not to be limited thereto, as the same is capable of receiving a variety of mechanical expressions as will now be apparent to those skilled in the art from the

foregoing explanation. Changes may be made in the details of construction, arrangement, shape, material, sizes, dimensions, etc., without departing from the spirit of this invention. Reference is therefore to be had to the claim hereto appended for a definition of said invention.

What is claimed is:

In a combined container and block, a substantially rectangular hollow body provided with parallel horizontal upper and lower walls, said upper wall being provided with a circular opening defined centrally thereof affording communication with the hollow interior of the block and of slightly less diameter than the width of said body, an upstanding cylindrical collar disposed about the periphery of said opening and extending an appreciable distance upwardly therefrom, the balance of the upper wall of said body constituting a horizontal and rectilinear shoulder surrounding said collar, a peripheral wall extending downwardly an appreciable distance below the lower wall of the hollow body forming a cylindrical base recess and a rectilinear shoulder surrounding said base recess, an outwardly extending beveled flange disposed about the outer upper periphery of said collar, a cover fitted over said flange to provide a relatively close fit between the outer periphery thereof and the interior wall of the cylindrical base recess of a superimposed container, whereby a series of said containers may be readily nested by inserting the collar of a lower container into the base recess of a superimposed container and registering said rectilinear peripheral shoulders.
